UNITED STATES PATENT OFFICE.

DAVID KILGOUR, JR., OF SEATTLE, WASHINGTON.

RATCHET PIPE CUTTER.

Application filed August 17, 1923. Serial No. 657,911.

To all whom it may concern:

Be it known that I, DAVID KILGOUR, Jr., a citizen of the Dominion of Canada, and resident of the city of Seattle, in the county of 5 King and State of Washington, have invented certain new and useful Improvements in Ratchet Pipe Cutters, of which the following is a specification.

My invention comprises an improvement 10 in pipe cutters, particularly of the type employing a ring rotatable by a handle through ratchet means.

It is an object of my invention to provide a simple and convenient ratchet pipe cutter 15 into which the pipe can be conveniently inserted.

A further object is the provision of means controllable through the handle for adjusting the various pipe engaging elements of 20 the cutter.

A further object is the provision of a ratchet pipe cutter employing a rotatable ring formed in two parts hinged together and the provision therein of a latch which 25 cannot be released while the pipe is in position therein and the pipe engaging elements engage the pipe.

A further object is the provision in a pipe cutter of this type, of means for adjusting 30 the various pipe engaging elements to accommodate the cutter to pipes of widely varying diameters.

A further object is the provision of a pipe cutter of the type described, in which the 35 various pipe engaging elements are so assembled that the parts which ordinarily will be worn out or require attention may be removed in a single unit for such attention.

My invention comprises those novel parts 40 and combinations thereof which are shown in the accompanying drawings, described in the specification, and particularly defined by the claims terminating the same.

In the accompanying drawings I have 45 shown my invention in the form which is now preferred by me.

Figure 1 is an elevation of my cutter, shown in operative engagement with a pipe.

Figure 2 is a view similar to Figure 1, 50 parts being broken away and shown in section, and the several parts of the cutter ring being shown disengaged.

Figure 3 is an axial section through Figure 1.

Essentially my cutter comprises a handle 55 3, a ring 2 and various pipe engaging and

cutting elements carried by the ring 2, such as the cutting disk 1 and the rollers 10 for supporting the pipe P opposite the cutting disk 1. The handle 3 I have shown as bifurcated at one end, the bifurcation being indicated at 30. The ring 2 is formed with grooves 20 extending about it, and the bifurcated end of the handle is provided with ribs 32 engageable in the groove 20 to support the ring from the handle for rotation about its center.

I have provided a ratchet connection between the handle 3 and ring 2 which may be of any desired form. This I have shown 70 as a spring pressed dog 33 mounted in the handle 3 and engaging teeth 23 formed in the periphery of the ring 2. It should be understood that the dog 33 is positioned at one side of the bifurcated end of the handle 75 and does not obstruct the bifurcation 30 therein.

The ring 2 is formed in two parts or segments which are hingedly connected by a pin 22. One of the segments, as 24, may be 80 easily detached from the other segment, 25, and the segment 24 preferably carries the pipe engaging elements 1 and 10. In order to secure together the free ends of the two segments I have provided the latch 26, pivoted to one of the segments and preferably held in place by a spring 27. This engages the opposite segment and may be disengaged as by pressure upon a handle 28 or by lifting a lug 29, to cause the latch to move toward the center of the ring. It will be seen from Figure 1 that when the pipe engaging elements 1 and 10 are in position properly to engage a pipe of any considerable diameter, the latch 26 cannot be lifted sufficiently to 85 release the two ends of the segments 24 and 25 without engagement of the pipe. Thus accidental disengagement of the latch 26 is prevented. Further, it will be noted that inasmuch as the latch swings towards the 90 center to open, the effect of any centrifugal force, as the ring 2 rotates, will be to maintain the latch closed.

Preferably the cutting disk 1 and the rollers 10 are not fixedly secured to the ring 105 2. It is essential, of course, that one of these elements be movable relative to the ring, although the other, as, for instance, the rollers 10, might if desired be fixed thereto. However, I have shown the disk 1 as journaled in an arm 11 pivoted at 12 to the segment 24. I have also shown the rollers 10 as 110

journaled in an arm 13 pivoted at 14 to the same segment 24.

A set screw 15 threaded in the segment 24 may be turned to adjust the position of the rollers 10 relative to the center of the ring. Likewise a screw or bolt 16 is provided, this being threaded through the ring 2 as is shown herein in the segment 25. Both of these screws 15 and 16 project from the periphery of the ring, and as the ring rotates they pass through the bifurcation 30 in the handle. It is evident that the head of the bolt 16 and of the screw 15 may be in any desired form. The screw 15 is shown as a thumb screw. The bolt 16 in Figure 2 has been shown as provided with a T-shaped handle 17, whereas in Figures 1 and 3 it has been shown as provided with a regular square or hexagonal head 18. The form of this head may be varied in any manner desired, care being taken that the head shall not be of a shape that will not pass through the bifurcation 30.

However, I prefer that it be formed in such manner as to accommodate a socket wrench 40 which is secured at the end of a rod 4, reciprocable in a bore 34 in the handle 3. The rod 4 at its upper end projects from the end of the handle and is provided with a suitable handle 41 enabling it to be turned easily. Thus, whenever the bolt 16 is in line with the rod 4, the socket wrench 40 may be depressed to engage the head 18 of the bolt and the bolt can then be adjusted to control the position of the cutting disk 1. Obviously, the wrench 40 may be of a shape to engage any shape of head which is rotatable in the bifurcation 30.

When it is desired to insert a new pipe, the latch 26 is released and the segments 24 and 25 swing apart. The bolt 16 and the screw 15 should be retracted and then the pipe is inserted. Due to retraction of the bolts 15 and 16, the pipe can be moved to one side to give sufficient room for the latch 26 to close. The bolts are then adjusted to engage the pipe with the cutting disk 1 and the rollers 10 and by rotation or oscillation of the handle 3, the ring 2 is rotated about the pipe. The device may be used either without the ratchet, by rotating the handle 3 entirely about the pipe with the ring 2, or the ratchet dog 33 may be brought into operation. If it is desired to remove the cutting disk for sharpening or for any other purpose, it is a simple matter to remove the segment 24. The rollers 10 can also be replaced in the same manner if they become damaged.

For cutting quite small pipes an auxiliary block 5 may be employed. I have shown the arm 11 as dove-tailed at 19 upon its upper surface, to receive a corresponding groove in the block 5. When the block is secured on the arm 11 it is interposed between the arm and the bolt 16, and moves the cutting disk closer to the rollers 10 by the thickness of the block.

What I claim as my invention is:

1. A pipe cutter comprising a handle bifurcated at one end, a ring guided in said bifurcated end for rotation about its center, ratchet means connecting the ring and handle, pipe engaging and cutting elements carried by said ring, a screw threaded in said ring and engaging the cutting element to control its position, the head of said screw projecting from the periphery of said ring and passing through the bifurcation of the handle as the ring is rotated relative thereto, and a socket wrench reciprocably mounted in said handle and engageable with the head of said screw to turn it when the two are brought into registry.

2. A pipe cutter including a ring rotatable about its center, said ring being formed of two hingedly connected segments, and a latch pivoted upon one segment and engaging the other segment to secure their free ends together, and movable toward the center of the ring to release.

3. A pipe cutter including a ring rotatable about its center, said ring being formed of two hingedly connected segments, a latch connecting the free ends of the two segments, an arm carrying a cutting disk and pivoted upon one of said segments, a second arm pivoted upon the same segment and carrying pipe-engaging rollers, and means for moving each of said arms to cause the pipe-engaging elements to approach or recede from the center of the ring.

4. A pipe cutter comprising a ring rotatable about its center, an arm pivoted by one end in the ring, a cutting tool in the opposite end of said arm, pipe-engaging and guiding means supported from the ring opposite said cutting tool, a bolt threaded in the ring and engaging the arm to control the position of the cutting tool, and an auxiliary block adapted to be interposed between the bolt and the arm, said arm and block having interengaging block-supporting means.

Signed at Seattle, King County, Washington, this 9th day of August 1923.

DAVID KILGOUR, JR.
